UNITED STATES PATENT OFFICE.

JOHN J. KINZER, OF PITTSBURG, PENNSYLVANIA, ASSIGNOR TO PITTSBURGH BRAKE SHOE COMPANY, OF PITTSBURG, PENNSYLVANIA, A CORPORATION OF PENNSYLVANIA.

BRAKE-SHOE.

SPECIFICATION forming part of Letters Patent No. 734,566, dated July 28, 1903.

Application filed February 27, 1903. Serial No. 145,322. (No model.)

To all whom it may concern:

Be it known that I, JOHN J. KINZER, of Pittsburgh, in the county of Allegheny and State of Pennsylvania, have invented a certain new and useful Improvement in Brake-Shoes, of which improvement the following is a specification.

The object of my invention is to provide a brake-shoe of simple, strong, and inexpensive construction, which may be maintained in operative condition without liability to breakage until substantially entirely worn out, and which may be securely attached to a brake head or hanger either with or without an independent strengthening-back.

The improvement claimed is hereinafter fully set forth.

In a separate application filed by me of even date herewith, Serial No. 145,324, I have set forth generically a brake-shoe consisting of an integral inclosing casing of strong and ductile material and a filling of frictional material secured therein.

My present invention is a specific embodiment of the above generic one, and relates more particularly to the construction of the casing in such form and manner as will be specially adaptable to the conditions of practical service.

In the accompanying drawings, Figure 1 is a front or face view of a brake-shoe illustrating an application of my invention, with the filling removed in order to show the construction more clearly; Fig. 2, a longitudinal central section through the same; Figs. 3 and 4, similar sections illustrating modifications of structural detail; Fig. 5, a rear view of the brake-shoe of Fig. 3; Fig. 6, a transverse section on the line *a a* of Fig. 2, with the filling removed; Figs. 7 and 8, similar sections on the lines *b b* and *c c*, respectively, of Fig. 3; Fig. 9, a rear view of the brake-shoe of Fig. 4, and Fig. 10 a transverse section on the line *d d* of Fig. 4.

In the practice of my invention I provide a brake-shoe comprising an inclosing casing 1 and a filling 3 inserted therein. The casing 1 is made of sheet or plate metal possessing a substantial degree of strength and ductility,

as steel, which is pressed or bent in suitable dies into a structure having integral back, side, and end walls and open at its front, and curved in substantial accordance with the periphery of the car-wheel to which it is to be applied. In order to afford increased strength, the side and end walls or the casing are preferably corrugated, and it may be further stiffened and strengthened by braces 1^b, which are secured to the casing by tongues 1^c, passing through slots in the walls of the casing and turned over thereon. Openings 1^d may be formed in the braces to reduce their weight and enable them to be engaged by the filling which fits in the spaces between them and between their outer faces and the walls of the casing. A hollow supporting-lug 2, through which the brake-shoe is connected to a brake head or hanger, is fixed to the back of the casing, said lug being either formed integral with the back wall of the casing, as shown in Figs. 3, 4, 7, and 10, or being separate therefrom and connected thereto by having its inner ends passed through slots in the back wall of the casing and turned over thereon, as in Figs. 2 and 6. In order to prevent the filling of the brake-shoe from entering the space within the lug 2, a liner 2^a may be fitted therein. Short bearing-faces 1^e, adapted to abut against bearings on the ends of a brake head or hanger, are formed on the back wall of the casing, adjoining its ends, said bearing-faces being preferably recessed. A separate and independent back may be interposed between the back wall of the casing and the brake-head for the purpose of strengthening the shoe and protecting the adjacent face of the head. A central bearing-face 1^f is also formed on the back wall, extending above and below the lug 2, to abut against central bearing-faces on the brake-hanger. Brake-shoes having the central bearing-face 1^f on their casings, as shown in Figs. 2, 3, and 5, may be used either with or without a separate back, as preferred, but if the casing is unprovided with said central bearing-face, as shown in Fig. 4, a separate back must be used in connecting the brake-shoe to the head or hanger.

The independent back referred to is not claimed as of my present invention and forms the subject of a separate application filed by me of even date herewith, Serial No. 145,323.

5 The rubbing or frictional action of the brake-shoe upon the wheel is exerted by a frictional member 3, consisting of a filling of any suitable material, as cast-iron (indicated in Figs. 4 and 10) or a composition of matter 10 specially prepared for the purpose (indicated in Figs. 3, 7, and 8) of such character as to exert proper and sufficient friction upon the periphery of a wheel without the imposition of undue or excessive pressure thereon, compositions of which character are familiar to 15 those skilled in the art. The filling 3 is either cast into the casing 1 when set in a mold or inserted in the casing under pressure and retained in position, after hardening, by the 20 walls of the casing.

A brake-shoe of the construction above described presents the substantial advantages of comparatively inexpensive construction, strength, lightness, and capability of use until 25 practically worn entirely away without liability to breakage as it becomes thin. In the use of shoes of the construction heretofore employed the tendency to crack and break when worn to the extent of about one-half and the consequent liability to derailment or injury to persons by flying fragments renders it necessary as a measure of precaution to remove and scrape them when so worn. The waste of material and loss of time involved in so doing are avoided by the employment 35 of brake-shoes embodying my invention.

I claim as my invention and desire to secure by Letters Patent—

1. In a brake-shoe, the combination of an 40 inclosing casing of sheet metal bent into integral back, side and end walls, a sheet-metal

lug fixed to the back of the casing, and a filling of frictional material.

2. In a brake-shoe, the combination of an 45 inclosing casing of sheet metal bent into integral back, side and end walls, and having strengthening-corrugations in its walls, and a filling of frictional material.

3. In a brake-shoe, the combination of an 50 inclosing casing of sheet metal bent into integral back, side, and end walls, strengthening-braces fixed to said casing, and a filling of frictional material.

4. In a brake-shoe, the combination of an 55 inclosing casing of sheet metal bent into integral back, side, and end walls, corrugated strengthening-braces fixed to said casing, and a filling of frictional material.

5. In a brake-shoe, the combination of an 60 inclosing casing of sheet metal bent into integral back, side, and end walls, a sheet-metal lug fixed to the back of the casing, a lining fitting said lug and partitioning its interior from the casing, and a filling of frictional material.

6. In a brake-shoe, the combination of an 65 inclosing casing of sheet metal bent into integral back, side, and end walls, with raised central and end bearing-faces in its back wall, a lug fixed to the back of the casing, and a 70 filling of frictional material.

7. In a brake-shoe, the combination of an 75 inclosing casing of sheet metal bent into integral back, side, and end walls, a separate sheet-metal lug fixed to the back wall of the casing by engagement with slots therein, and a filling of frictional material.

JOHN J. KINZER.
